(57) **CLAIM**

The ornamental design for a roof box for vehicles, as shown and described.

DESCRIPTION

FIG. 1.1: Front, right perspective view;

FIG. 1.2: Rear, right perspective view;

FIG. 1.3: Front view;

FIG. 1.4: Rear view;

FIG. 1.5: Right side view; and

FIG. 1.6: Front, right perspective view, in an unfolded configuration.

The left and right side views are mirror images.

The broken lines illustrate portions of the roof box for vehicles which form no part of the claimed design.
